UNITED STATES PATENT OFFICE.

BILLY FRANK CONAGHAN, OF TONKAWA, OKLAHOMA, ASSIGNOR OF ONE-FOURTH TO HOWARD M. GILLESPIE AND ONE-HALF TO WILLIAM J. BEAVEN.

CASING RING.

Application filed December 15, 1923. Serial No. 680,862.

To all whom it may concern:

Be it known that I, BILLY FRANK CONAGHAN, a citizen of the United States, and a resident of Tonkawa, in the county of Kay 5 and State of Oklahoma, have invented certain new and useful Improvements in Casting Rings, of which the following is a specification.

This invention relates to casing rings especially adapted for use in oil well operations.

An important object of this invention is to provide a sectional casing ring or elevator which may be conveniently attached to or 15 removed from a casing, a tubing or the like, without injuring the operator.

A further object is to provide a casing ring or elevator which may be conveniently adjusted for connection with casings of different diameters.

A further object is to provide a casing ring which is of highly simplified construction, durable in use and cheap to manufacture.

Other objects and advantages will be apparent during the course of the following description.

In the accompanying drawing, forming a part of this application, and in which like numerals are employed to designate like parts throughout the same,

Figure 1 is a perspective of the improved casing ring or elevator,

Figure 2 is a detail transverse sectional view on the line 2—2 of Figure 1,

Figure 3 is a group perspective of the improved elevator,

Figure 4 is a perspective of a bushing embodied in the invention and by means of which a casing of a reduced diameter may be supported,

Figure 5 is a perspective of one of the sections of the bushing.

In the drawing, wherein for the purpose of illustration is shown a preferred embodiment of the invention, the numerals 5 designate coacting substantially similar sections, the opposite side of which are formed with semi-circular recesses to receive a well casing, a tubing or the like. The semi-circular recesses of the spider or the ring in Figure 1 are tapering: i. e., larger at the top than bottom. The slips 3 shown in Figure 1 are fitted in the recesses which equalize the 50 diameter of the said recess and the grooves

therein together with the wedge effect obtained by tapering walls gives a firm grip on the casing or tubing.

The ends of the sections 5 are provided with extensions 6 having longitudinal grooves 8 which define ribs 9 and Figure 2 illustrates that longitudinal ribs 9 are adapted to be snugly received in the grooves 8 of opposite sections so that when assembled the parts will occupy the position illustrated in Figure 1.

However, attention is directed to the fact that each rib 9 is substantially less in thickness than the thickness of the major part of the section 5, and consequently the 70 grooves 8 may be made more or less shallow and do not in any way lessen the strength of the ring.

The extension 6 and the ribs 9 thereon are formed with transverse aligned openings 12 75 adapted for the reception of bolts or other connecting members 14 by means of which the sections may be securely connected to a casing. When the sections of the device are assembled as in Figure 1, the accidental separation of the sections is absolutely prevented and furthermore the interlocking connections between the extensions 6 and the ribs 9 positively prevent more strain taking place on one section than on another, or all 85 the strain from the casing being borne by one section alone.

If it is desired to reduce the internal diameter of the casing ring a liner or bushing 30 may be employed and as illustrated in 90 Figures 4 and 5, the liner or bushing may consist of a pair of semi-circular sections 31, the upper ends of which are provided with a laterally projecting flange 32 which overlies the upper side of the ring and holds the liner or bushing in place. The walls of the liner or bushing are tapering giving the same wedge-like effect when the weight of the casing is released on the ring.

The slips 3 illustrated in Figure 1 fit on 100 the inside of the liner and are so moulded as to make the recess where the pipe is received the same diameter at the top and bottom; i. e., the walls of the slips are thicker at the top than at the bottom. The slips 105 are formed with transverse teeth as shown in Figure 1 in order to make a firmer grip on the pipe or tubing. The slips are used with or without the liner.

In carrying out the invention, the sections 110

of the ring may be provided with loops 20 by means of which the ring may be conveniently lifted.

Having thus described the invention, what is claimed is:—

A casing ring comprising a pair of substantially semi-circular sections having their ends formed with extensions, each extension being formed with a longitudinal groove 10 and a longitudinal rib, each rib forming

one side wall of the adjacent groove and being adapted to be snugly received in the groove of the opposite section to interlock the sections, bolts passing through said extensions and the ribs of the same to securely 15 connect the sections, a bushing received between said sections and consisting of a pair of semi-circular members having a flange engaging the upper side of said sections.

BILLY FRANK CONAGHAN.
